UNITED STATES PATENT OFFICE.

CONRAD TÜTSCH, OF WINTERTHUR, SWITZERLAND.

BLEACHING-BOILER PLANT.

1,335,925.

Specification of Letters Patent.

Patented Apr. 6, 1920.

Application filed September 21, 1918. Serial No. 255,081.

To all whom it may concern:

Be it known that I, CONRAD TÜTSCH, a citizen of the Republic of Switzerland, residing at Winterthur, in the Canton of Zurich, Republic of Switzerland, have invented certain new and useful Improvements in Bleaching-Boiler Plants; and I do hereby declare the following to be a full, clear, and exact description of the invention, such as will enable others skilled in the art to which it appertains to make and use the same, reference being had to the accompanying drawings, and to reference-numerals marked thereon, which form a part of this specification.

In the construction of bleaching boilers, the following is to be kept in view as a principal object: The fabric to be bleached should be traversed by the bleaching medium as copiously and uniformly as possible and freed from air at a high boiling temperature, while the fabric must not be subjected to too severe treatment. It is also desirable to economize in the use of boiling lye, steam, labor and cost of manufacture and to simplify construction and working. The efficiency of such a plant is considerably increased if there is a possibility of quickly heating-up the fabric to be treated and such quick heating-up is possible only if the fabric is sufficiently penetrated by the bleaching medium from the beginning. The heating-up and the penetration have therefore a mutual and assisting reaction upon each other because the permeability of the fabric to be boiled is low at low temperature and progressively increases with increasing temperature, vice versa, the heat that is necessary for increasing the temperature will enable the lye to penetrate the fabric more rapidly and more copiously as the fabric is traversed by the lye.

In order to produce a copious circulation of the lye, the latter is forced generally through the fabric by means of a pump at a considerable pressure. But this pressure must not exceed a certain amount, otherwise the fabric which is difficult of penetration by the lye, so long as the fabric is not heated up, will be so compressed as not to allow the lye to pass through it. An efficient maximum pressure of the circulating lye is therefore to be employed for the fabric to be bleached, and consequently there is a need to enable this efficient maximum pumping pressure to be exactly adjusted

for each kind of fabric that is bleached. A careful distinction is to be made between the boiling pressure caused by the boiling of the lye in the outer boiler even when the pump is at rest, and the pumping pressure which results from the action of the pump and exceeds the boiling pressure so that the inner boiler is exposed to an inner over pressure, represented by the difference indicated by the pressure-gages connected to the branches of the inner boiler containing the fabric to be bleached.

The present invention has for its object to satisfy the above stated conditions in a simple manner. This object is effected substantially by providing in the outer boiler in which the higher boiling pressure is generated, an inner boiler capable of being closed tight independently, which receives the fabric to be treated and is exposed in its interior to the pumping pressure, which is only little higher than the boiling pressure prevailing on the outside of said inner vessel. The latter can therefore be made considerably lighter than the outer boiler. A space is left practically all around the inner boiler and owing to this space existing between the two boilers, the heat can pass directly through the walls of the inner boiler.

In the known boiling plants, the initial heat supply to the fabric is small on account of the fact that the circulation of the boiling lye is greatly obstructed at first. With the present invention, however, the supply of heat to the fabric is assisted in such a degree that the heating up period will be reduced to a minimum. The value of this arrangement is best shown by the fact, that the actual process of dissolving impurities contained in the fabric, which process is effected by the boiling lye, begins rightly only at temperatures of more than 100° C., and that in other apparatus the duration of heating-up occupies a quite substantial part of the total boiling duration. Therefore in contra-distinction to the known plants employing a circulation of the boiling liquid, the present improved apparatus has among other advantages the additional advantage that the duration of the heating-up of the fabric is considerably shortened and also the efficiency increased.

By employing two boilers, the outer one of which is exposed to the boiling pressure while the inner one contains the fabric to

be bleached, and also the pumping pressure, it is possible to use the most favorable pumping pressure for each kind of fabric. There is no difficulty in constructing the apparatus in such a manner that a certain amount of pumping pressure (in the form of surplus lye) may automatically escape from the inner boiler when the pumping pressure exceeds its most favorable amount.

10 In the accompanying drawings which illustrate two constructional examples of this invention with details:—

15 Figure 1 is an elevation partly in vertical section of the first example consisting of a plant with vertical boilers.

20 Figs. 2 and 3 are respectively a longitudinal section and a cross section of the second example, consisting of a plant with horizontal boilers.

25 Fig. 4 is a diagrammatic view of a four way cock used on said boilers;

Fig. 5 illustrates a self-acting valve, and

Fig. 6 is a sectional detail of the branch leading from the outer boiler.

30 Referring to Fig. 1: 1 is the inner boiler and 2 is the outer boiler. The inner boiler consists of two basket-like parts 3 and 4 placed one on the other with a cover 5. The upper basket has a straining bottom 6 to let the lye through. A straining bottom 6^a of this kind is also arranged in the lower basket part at a certain distance away from the solid bottom 5^a and a strainer top or cover 6^b is arranged within the boiler cover

35 5. The straining top 6^b is likewise arranged a certain distance away from the solid cover 5. They allow a uniform entry and exit of the lye to and from the whole of the fabric to be bleached, and they prevent the orifices of the branches 11 from being stopped up.

40 In the case where fabrics spread out *i. e.*, not in the hank, are to be placed into the baskets 3 and 4 through an opening in the side wall thereof, when the baskets are outside the boiler 2 and rest on their side wall, the upper basket is preferably provided with a straining cover 6^c parallel to the straining bottom 6 (see dash dotted line in Fig. 1).

45 55 The outer boiler 2 is connected to its cover 7 by means of flanged rings 8. The lower flange is provided with a groove receiving a rib of the upper flange, bolts 9 being provided for clamping the flanges together. Below the inner boiler there is arranged a heating coil 10 in the outer boiler.

60 65 Both at top and bottom the inner boiler 1 is connected to the circulation pipe by branch pipes 11 fitted on to its domed bottom and cover respectively. This branch 11 is provided with a lateral discharge branch 13 controlled by a valve 12. Fig. 5 shows these parts on a larger scale. The rod 14 of the valve 12 is jointed at one end to a bell crank lever 15, 15^a, and at its other end it is

guided with some play in a lateral projection 16 of the branch 11. The arm 15 of the bell crank lever is arranged on the exterior of the apparatus and carries an adjustable weight 17 which presses the valve member 12 against its seat so long as the pressure in the branch 11 does not exceed a certain amount.

The two branches 11 are connected to each other by a pipe 18 having a detachable coupling 19. By detaching the upper part of the pipe 18 the boiler covers can be removed for the purpose of removing the fabric from or placing it into the boiler 1 or the boiler 1 itself can be taken out. A four way cock 20 (Fig. 4) is fitted in the pipe 18. It serves to connect the latter with either the delivery pipe 21 of a pump 22, or, with a branch 23 leading to the outer boiler 2 on the other. This four way cock 20 is provided with a partition 24 capable of being turned in a well known manner. When this partition occupies the position shown in Fig. 4 in full lines, the upper part of the pipe 18 is connected with the branch 23, and the lower part of 18 is connected with the delivery pipe 21. After turning this partition 24 into the position indicated in dash-dotted lines the branch 23 is connected with the lower part of the pipe 18, and the delivery pipe 21 is connected with the upper part of the pipe 18. The branch 23 is so arranged on the boiler 2 as to cause the boiling lye to enter the latter in a tangential direction whereby it receives a circular motion around the axis of the boiler and thus comes intensively into contact with the heating coil 10 (Fig. 6).

Two three way cocks 26, 26^a are fitted in the suction pipe 25 of the pump 22, which connects the pump with the lower end of the outer boiler 2. When the cock 26 is in one position it connects this end with a discharge branch 27. The cock 26^a serves to connect the pump to an admission branch 27^a that leads to a water container or the like.

A cock 28 provided on the upper part of the boiler 2 serves to admit lye, rinsing water &c. Pressure-gages 29 are connected to the upper and lower parts of the pipe 18. On the cover of the outer boiler 2 and on top of the pipe 18 air-escape cocks 30, 31, 31^a are provided. A ring 32 on top of the entire plant serves for removing and transporting the boiler covers by means of lifting tackle, traveling cranes or the like.

The herein described bleaching boiler plant operates as follows:—

First, boiling lye is admitted through cock 28 into the boiler 2, this lye accumulates at first around the heating coil 10 and in the cylindrical space between the two boilers. The three way cocks 26, 26^a are operated to connect the boiler 2 with the pump 22, while the branches 27, 27^a are

closed, so that lye flows from the outer boiler 2 through the pipe 25 to the pump 22 by gravity. The pump 22 is started shortly before the cock 28 is opened. The partition 24 of the four way cock is moved into the position shown in full lines in Fig. 4, so that the lye supplied by the pump 22, will flow from the delivery pipe 21 into the lower part of the pipe 18 and from below into the inner boiler 1, driving the air contained in the latter out in front of it. Lye is pumped into the inner boiler until lye flows off through the opened air-escape cock 31, and sufficient reserve fluid has accumulated above the heating coil 10 and in the cylindrical space between the two boilers. This may be ascertained by means of a water gage 41 mounted on the outside of the boiler 2 and a mark 42 situated behind said water gage.

When this stage has been reached, the admission cock 28 is closed, likewise the air-escape cock 31, while the air-escape cock 30 remains temporarily closed until a considerable generation of steam has begun.

The lye leaving the inner boiler 1 at the top flows through the upper part of the pipe 18, the four way cock 20 and the branch 23 back to the heating apparatus, where it is heated again and repeats the cycle of circulation.

At the commencement of the bleaching process the fabric to be bleached will oppose the greatest resistance to the passing through of the lye in the boiler 1 and will act in the manner of a plug. In consequence, pressure is produced in the lye below the fabric. As soon as this pressure reaches a certain amount which may be predetermined, the lower valve 12 will automatically come into operation so as to allow surplus lye to pass from boiler 1 into the pipe 25 and outer boiler 2.

In order that the lye shall flow through the fabric with the greatest possible uniformity, and the fabric shall be freed from air as much as possible, the flow of the lye must be reversed from time to time. This is effected by turning the partition 24 of the four way cock 20 into the position indicated by the dash dotted line. The lye will now flow from the delivery pipe 21 into the upper part of pipe 18 and into boiler 1 from the top, and leave the latter through the lower branch 11 and flow through the lower part of pipe 18 to cock 20 and thence through branch 23 into the outer boiler 2 back to the heating coil 10. If with this direction of flow the pressure on top of the boiler 1 exceeds the desired amount, the upper valve 12 will open and allow the surplus lye to flow back into boiler 2.

It will be seen from the foregoing that in each direction of flow of the lye, the outer and the inner boiler are disposed one be-

hind another with regard to the flowing of the lye, viz. the lye flows from the pump 22 through pipe 21, cock 20 to one or the other end of the inner boiler 1, penetrates the fabric in the latter, leaves this boiler at its other end, flows through the upper or the lower part of the piping 18 through cock 20 and branch 23 into the outer boiler 2 and returns to the pump 22 through pipe 25.

The described cycle of the boiling lye allows also of operating with only a partial filling of the inner boiler. In this case however the lye can only flow downward and is raised by the pump to the top of the inner boiler, and trickles through the material undergoing bleaching by gravity alone.

The heating of this partial charge of lye may be accelerated by frequently stopping the pump 22. In this manner the lye is allowed each time to accumulate around the heating coil 10 and become heated while it is at rest.

The cooling of the warmed-up boiler contents (fabric and lye) and the regaining of the heat therefrom may at first be effected in the known manner by conducting cooling water through the heating coil 10. When in this way the boiling lye has cooled down to about 100° C. it is discharged through the pipe 27. Thereupon the suction branch of the centrifugal pump is connected by the three way cock 26^a and the branch 27^a with a cooling water container or the like and cooling water is driven by the pump through the inner boiler and around it in the same manner as before with the lye.

In the plant shown in Figs. 2 and 3 consisting of horizontal boilers, the inner boiler 1 rests upon rollers 36 by means of channel bars 35 extending around the greater part of its circumference. This setting allows of turning the boiler on its axis within wide limits. This is of importance for charging the boiler. The rollers 36 are supported by a carriage 37 running on rails 38 fixed to the shell of the outer boiler 2.

The inner boiler is provided on top with a wide charging aperture 39 which may be properly closed by means of a cover 40.

In other respects the construction and function of this plant are similar to those of the one hereinbefore described. In order to place the fabric to be treated into boiler 1, the front ends 5 and 7 of the boilers with their fittings are removed from the boilers by means of traveling cranes or the like after undoing the bolts 9. The rails 38 are connected with rails in the floor of the work room in question by means of inset rails 41. Then the inner boiler 1 is drawn out, for instance under a charging machine, distributing apparatus or the like. During the charging operation it remains at first in the position shown in Fig. 3. As soon as it is filled to say about half it is turned around

to the left by an amount such that its upper left hand quadrant comes under the charging opening 39. Then the boiler is returned into about its initial position, and now the 5 last (right hand upper) quadrant of its section is charged.

When the charging is completed, the 10 boiler 1 is returned into the boiler 2 and the connection is made. Then lye is admitted 15 through cock 28 into the outer boiler and heated by the heating coils 10. Afterward the pump 22 is started and the lye is forced at one time from the left and another from the right through the inner boiler and the 20 fabric, &c., as described with reference to Fig. 1.

From the foregoing it will be evident that 25 by means of the weighted valve 12 the highest pressure in the inner boiler may be 30 adjusted at will, according to the kind of fabric to be bleached, by adjusting the weight 17.

The heating coil is made removable in order 35 that the unavoidable formation of scale may be counteracted with the most simple means and with the least loss of time.

The nature of the fabric to be bleached 40 will decide whether an inner boiler made in one part or in more parts or baskets is used. For cotton fabrics of medium quality 45 in the form of hanks the construction in one piece will be preferred, whereas for cotton fabrics woven very closely and therefore of low permeability having strongly 50 twisted threads, as well as for yarn in the hank, cross-wound spools &c., inner boilers consisting of more than one part will be 55 more advantageous. The latter kind of boilers are adapted especially for the boiling of cotton fabrics in broad pieces, so called 60 broad bleaching. The inner boiler may be made of a plurality of parts also when it is horizontally arranged. The inner boilers built-up of a plurality of parts offer more- 65 over the advantage, that when the bleaching process is finished, that they can be lifted out immediately from the vertical boiler by means of lifting tackle, traveling crane, &c., and replaced by new freshly charged 70 baskets. In this way the vertical boiler also can be rendered available again for the boiling process after the shortest intervals of time.

Contrary to the outer boiler the inner 75 boiler does not come under the steam boiler regulations because it need be kept tight only to a limited degree; and even if it were to break down through the pumping pressure, this would not involve any danger of 80 explosion of the outer boiler. The inner boiler has to bear a very low inner over-pressure compared with the pressure in the outer boiler, said over-pressure (difference 85 between inner and outer pressure) amounting at most to $\frac{1}{4}$ atmosphere. Consequently

it can be made very much lighter than the outer boiler, which latter has to bear the greater difference between the boiling pressure and the atmospheric pressure.

The use of an inner boiler includes among 70 other things the advantage that the outer boiler can be more easily adapted to the requirements of the steam boiler regulations. It need only be mentioned here that considerable difficulties are met with in the 75 proper making of the longitudinal seam on the cylindrical shell of the ordinary bleaching boilers especially in countries where autogenous welded seams are prohibited in the ordinary high pressure bleaching boilers. 80 It would then be necessary to return to strap riveting. Owing however to the fact that a strap cannot be used on the inside of the single boiler because at this place the fabric to be bleached would be rubbed to pieces 85 against the said strap, it would be necessary to employ a single outside strap. But such a strap is subjected to very great strain and in consequence is liable to the risk of cracking at the butting ends of the shell plate 90 without the beginning of said cracking being perceived in time when the boiler is inspected. Danger of explosion would arise therefore in time.

When an inner boiler is used, outer and 95 inner straps may be employed together without disadvantage, thereby producing a very strong connection.

What I claim is:—

1. In an apparatus for treating textile 100 fabric by means of heated liquid, a separate inner boiler (1) for receiving the textile fabric, a boiler (2) surrounding the inner boiler on all sides and shut off from the outer air, for heating the contents of the inner 105 boiler, and a piping (18) connected to both ends of the inner boiler, leading beyond the outer boiler and connected with the interior of the outer boiler.

2. In an apparatus for treating textile 110 fabric by means of heated liquid, a separate inner boiler (1) for receiving the textile fabric, a boiler (2) surrounding the inner boiler on all sides and shut off from the outer air, for heating the contents of the inner 115 boiler, a piping (18) connected to both ends of the inner boiler, leading beyond the outer boiler and connected with the interior of the outer boiler, and a conveying pump (22), having its delivery pipe 120 connected to said piping (18).

3. In an apparatus for treating textile 125 fabric by means of heated liquid, a separate inner boiler (1) for receiving the textile fabric, a boiler (2) surrounding the inner boiler on all sides and shut off from the outer air, for heating the contents of the inner boiler, a piping (18) connected to both ends of the inner boiler, leading beyond the outer boiler and connected with the interior 30

of the outer boiler, a conveying pump (22), having its suction pipe (25) connected to the outer boiler (2), and its delivery pipe (21) connected with said piping (18), and a device (20) for causing direction of flow in this piping to be changed.

4. In an apparatus for treating textile fabric by means of heated liquid, a separate inner boiler (1) for receiving the textile fabric, a boiler (2) surrounding the inner boiler on all sides and shut off from the outer air, for heating the contents of the inner boiler, a piping (18) connected to both ends of the inner boiler, leading beyond the outer boiler and connected with the interior of the outer boiler, a conveying pump (22), the suction pipe (25) thereof being connected to the outer boiler, a delivery pipe connecting the pump with side piping (18), a conduit connecting the piping (18) to the outer boiler, a reversing device (20) located in the piping 18 for causing circulating fluid from the pump to pass to one portion or another portion of the piping 18, this reversing device being adapted to connect the delivery pipe alternately to one or the other end of the inner boiler, while that end of the latter, which is for the time not connected to this delivery pipe (21), is connected by means of said reversing device, to the space between the two boilers.

5. In an apparatus for treating textile fabric by means of heated liquid, a boiler (1) for receiving the textile fabric, another boiler (2) surrounding the inner boiler on all sides and shut off from the outer air for heating the contents of the inner boiler, a piping (18) connected to both ends of the inner boiler, a conveying pump (22), a reversing device (20) connecting the delivery pipe of this pump with the piping (18) and causing to connect said delivery pipe (21) alternatively with one or the other end of said inner boiler, and an adjustable valve (12) placed in said piping between each end of the inner boiler and the reversing device and adapted to open outwardly toward the outer boiler when the pressure in the respective branch of the piping (18) reaches a predetermined amount.

6. In an apparatus for treating textile fabric by means of heated liquid, a boiler (1) for receiving the textile fabric, another boiler (2) surrounding the inner boiler on all sides and shut off from the outer air for heating the contents of the inner boiler, a piping (18) connected to both ends of the

inner boiler, a conveying pump (22), the suction pipe (25) of this pump being connected to the space between the boilers, the delivery pipe (21) of said pump being connected with said piping (18), a four-way reversing means (20) inserted in this piping and connected on one side with the delivery pipe of said pump and on the opposite side with the hollow space between both boilers, said reversing means being thus adapted to connect said delivery pipe alternately with one or the other end of the inner boiler and to connect at the same time that end of said inner boiler which is not connected with the delivery pipe, with the space between both boilers, and an adjustable valve (12) in said piping (18) between each end of the inner boiler and the said four-way reversing means, adapted to open automatically as soon as the pressure in the respective part of said piping reaches a predetermined amount.

7. In an apparatus for treating textile fabric by means of heated liquid, a boiler (1) for receiving the textile fabric, an outer boiler (2) surrounding the inner boiler on all sides and shut off from the outer air for heating the contents of the inner boiler, the latter resting upon rollers (36) mounted on a carriage provided in the space left between both boilers, having their axis parallel to the horizontal axis of the boilers and allowing said inner boiler to be rotated on its own stationary axis, a piping (18) connected to both ends of the inner boiler, a conveyer pump (22), the suction pipe (25) thereof being connected to the space left between both boilers, a four-way reversing cock (20) connected on one side to said space and on the other side to the delivery pipe of said pump and adapted to connect said delivery pipe alternately with one or the other end of the inner boiler and at the same time connect that end of the inner boiler which is at the time not connected to the delivery pipe, to the space left between both boilers, and an adjustable valve (12) inserted in said piping (18) between each end of the inner boiler and said four-way reversing cock and adapted to open automatically toward the space between both boilers as soon as the pressure in said piping (18) reaches a predetermined amount.

In testimony whereof, I have signed my name to this specification.

CONRAD TÜTSCH.
